DESIGN FOR A CANDLE HOLDER

Byron G. Newton, Syracuse, N. Y., assignor to
Mack Miller Candle Co., Syracuse, N. Y., a
corporation of New York

Application October 12, 1936, Serial No. 65,262

Term of patent 14 years

To all whom it may concern:

Be it known that I, Byron G. Newton, a citizen
of the United States, residing in the county
of Onondaga, city of Syracuse, State of New
York, have invented a new, original, and orna-
mental Design for a Candle Holder, of which the
following is a specification, reference being had to
the accompanying drawing, forming part there-
of.

Figure 1 is a perspective view of a candle holder
showing my new design.

Figure 2 is a top plan view.

Figure 3 is a side elevation.

I claim:

The ornamental design for a candle holder, as
shown.

BYRON G. NEWTON.
